PORTABLE PLUG-IN ELECTRIC METER FOR REMOTELY READING METERS IN BUILDINGS OR SIMILAR ARTICLE

Harry Ehrensaft, Skokie, Ill., assignor to Muntz TV, Inc.,
Wheeling, Ill., a corporation of Illinois

Filed May 8, 1963, Ser. No. 74,805

Term of patent 14 years

(Cl. D26—1)

FIGURE 1 is a front perspective view of a portable plug-in electric meter for remotely reading meters in buildings or similar article showing my new design;

FIGURE 2 is a top plan view;

FIGURE 3 is a rear elevational view;

FIGURE 4 is a front elevational view;

FIGURE 5 is a left side elevational view;

FIGURE 6 is a right side elevational view; and

FIGURE 7 is a bottom plan view.

I claim:

The ornamental design for a portable plug-in electric meter for remotely reading meters in buildings or similar article, as shown.
